UNITED STATES PATENT OFFICE.

ISAAC LEVIN, OF BROOKLYN, NEW YORK.

DRESS-FORM.

No. 905,333.

Specification of Letters Patent.

Patented Dec. 1, 1908.

Application filed April 2, 1907. Serial No. 366,016.

To all whom it may concern:

Be it known that I, ISAAC LEVIN, a citizen of the United States, residing at Brooklyn, Kings county, in the State of New York, have invented certain new and useful Improvements in Dress-Forms, of which the following is a clear, full, and exact description.

This invention relates to garment forms, particularly to that class used for the purpose of hanging or draping garments, the object of the invention being to provide a practical garment form which can be readily adjusted to suit different measurements and which can be folded into a compact structure when not in use.

A further object of my invention is to provide a simple self-locking adjusting element by which the frame members of the said form can be adjusted, in combination with other elements which will hereinafter appear.

In the accompanying drawings, forming part of this specification,—Figure 1 illustrates a side elevation of a garment form embodying my improvements; Fig. 2 is a central vertical sectional view thereof, the central shaft being shown in elevation and the frame at the back having been omitted for greater clearness; Fig. 3 is an enlarged detail view of the self-locking adjusting means; Fig. 4 is an enlarged cross-sectional view thereof, the view being taken on a line *a—a* in Fig. 3, looking in the direction of the arrow; Fig. 5 is a top plan view of the binding element for the frame-wires and which also supports the adjusting elements; Fig. 6 is a perspective view thereof; Fig. 7 is an enlarged side elevation of the central shaft; Fig. 8 is a top plan view thereof; and Fig. 9 is a cross-sectional plan view of my improved garment form, the section being taken on a line *b—b* in Fig. 1.

Like numerals of reference are intended to indicate corresponding parts in the several views.

In the accompanying drawings, the numeral 1 indicates the central shaft of my improved garment-form, which at its upper end is enlarged, as at 2, a portion 3 of which is threaded left-handed, and a portion 4 threaded right-handed. Upon said left and right-handed portions, collars 5 and 6 are

adapted to travel, said collars being threaded to correspond to the threads upon which they travel, in obvious manner. From the collars 5 and 6 ribs 7 and 8, respectively, extend to binding-elements 9. Said binding-elements have an inwardly extending member 10 (see Fig. 6) to which said ribs 7, 8 are connected at the outer ends thereof. An eye or passage 11 is also provided upon said binding element, through which I reave a measuring tape 12. The binding element 9 is preferably struck from one piece of metal for purposes of economy. The region of the binding elements 9 correspond approximately to the waist-line. Intermediate 65 of the top and bottom of the figure or form binding elements 13 are positioned, said position corresponding approximately to the hip-line. The binding elements 13 are of the same construction as the elements 9. Adjacent to the hip region a collar 14 is slidably mounted on the shaft 1, and from said collar to the elements 13 self-locking adjusting-ribs 15 are extended, which are composed of the members 16 and 17, offset as at 18, said members 16 and 17 contacting each other at the surfaces 19 (see Fig. 3). After the members 16 and 17 are placed together, their ends are turned over to form an eye 20, the eye 20 of one member embracing the opposite member (see Fig. 4). When the eyes are bent or formed, they draw the members 16 and 17 firmly together, thereby creating a strong frictional contact, and when said members are moved for adjusting purposes 80 85 90 they will stay where put, thus forming an automatic lock.

Through the eyes 11 of the binding elements 13, I reave a measuring tape 22. Adjacent to the bottom of the form, I place binding elements 22, which are formed the same as the elements 9 and 13, only without eyes. The said lower binding elements 22 are connected to a slidable collar 23 by adjustable ribs 25, which, like the ribs 15, are composed of the slidable members 26 and 27. As the last named ribs are made the same way as the ribs 15, no further detailed description thereof will be given. The collar 23 is held in the desired position by a binding-screw 24. The bottom of the flexible wire-frame members 29 of the form are held by binding elements 30, preferably made of one piece. The binding-elements 9, 13, 22 and 30 are provided at the ends thereof with 100 105 110

eyes or passages such as the eyes 31 shown in Fig. 6. Through these eyes the frame-wires 29 are passed, as will be seen in Fig. 2, and frictionally held substantially in the 5 manner shown in Figs. 1 and 2. The shaft 1 may be held by any suitable base, such as 32 in Fig. 1.

As will be seen by Fig. 9, each pair of ribs 10 are of forked formation, that is, form a fork-like structure, the inner ends 33 being pivotally held in jaws 33^a integral with the collar 23, which can be cast, drop-forged or stamped. The collar 23 and ribs 25 have been selected for illustration, the same construction being used for the collars 6, 5 and 15 14 and ribs 7, 8 and 16, respectively.

The ribs 29 can be drawn in, or forced outwardly, as will be seen by the dotted lines 34 and 35 in Fig. 2, the waist-line dimension 20 remaining the same. The waist-line dimension can be changed at will by revolving the form on its shaft, whereby the collars 5 and 6 can be caused to approach or recede, due to the right and left-hand threads 3 and 25 4. In other words, by means of my improved construction, I can get any desired waist-line dimension without changing the hip dimension, or I can change the hip dimension without changing the waist 30 dimension. I can also produce a flat or full front without changing the hip or waist dimension, the various changes which I can produce being too obvious for detailed description.

To make the various changes it 35 is simply necessary to pull the adjustable rib-members outwardly or push them inwardly to the desired extent, the frictional contact between said rib-members holding them in the adjusted position, as has heretofore been explained, whereby the necessity 40 of manually operated locking devices is obviated. To fold the form, it is but necessary to push the frame-wires 29 and adjustable ribs inwardly, whereby the structure 45 will fold, in the manner of an umbrella. The tapes 12 and 22^a can be used to get the dimensions of the various hip and waist-line changes, and by means of the adjustable ribs,

it is possible to readily adjust each of the frame-members to the desired position. 50

Referring to Fig. 2, particularly to the parts 3 and 4 upon the central shaft 1, it will be seen that the collars 5 and 6 on said threaded portions 3 and 4 respectively, are both connected by the ribs 7 and 8 to the 55 binding elements 10, which, as has been hereinbefore stated, are at a position corresponding to the waist line of the human figure, and, as has also been stated, the said waist line portion can be increased or decreased in diameter by simply rotating the dress-form upon the central shaft 1. This obviates the necessity of manipulating the said collars 5 and 6 independently, and the particular object of this construction is to provide a 60 dress-form, the waist line of which can be adjusted from the outside or exteriorly of the garment form when a garment is being draped thereon, thus obviating the necessity of disturbing the garment. The dress-form 65 can be rotated upon the shaft 1 by simply easing up the set screw 24 in the collar 23.

Having now described my invention, what I claim and desire to secure by Letters Patent is:

A foldable garment-form, comprising a plurality of flexible frame-members suitably supported, means whereby said frame-members can be independently adjusted, the waist line of said form being adapted for adjustment, a plurality of ribs connecting said waist line and an adjusting device carried by the central shaft of said form at the upper end thereof, said adjusting device comprising a right and left hand thread, collars 75 carried by said threads adapted to retain the inner ends of said ribs, said collars being simultaneously actuated by the revolution of said garment form, whereby the said collars are caused to approach each other, or to recede, whereby the waist line is increased or decreased. 80

ISAAC LEVINE.
